UNITED STATES PATENT OFFICE

167,273

INFANT NURSING BOTTLE

Benjamin Nusbaum, Washington, D. C.

Application March 21, 1951, Serial No. 14,574

Term of patent 14 years

(Cl. D83—8)

To all whom it may concern:

Be it known that I, Benjamin Nusbaum, a citizen of the United States, residing at Washington, in the District of Columbia, have invented a new, original, and ornamental Design for an Infant Nursing Bottle, of which the following is a specification, reference being had to the accompanying drawing, forming a part hereof.

Fig. 1 is a view in perspective,

Fig. 2 is a side elevation,

Fig. 3 is an enlarged bottom plan view, and

Fig. 4 is a side elevational view of an infant nursing bottle, showing my new design.

I claim:

The ornamental design for an infant nursing bottle, as shown.

BENJAMIN NUSBAUM.
